DESIGN FOR A DRESS OR SIMILAR ARTICLE

Harry Langer, New York, N. Y.

Application September 16, 1940, Serial No. 95,110

Term of patent 3½ years

To the Commissioner of Patents:

Be it known that I, Harry Langer, a citizen of the United States, residing at 300 Central Park West, in the county of New York and State of New York, have invented a new, original, and ornamental Design for a Dress or Similar Article, of which the following is a specification, reference being had to the accompanying drawing, forming part thereof.

I claim:

The ornamental design for a dress or similar article, substantially as shown.

HARRY LANGER.
